(57) **CLAIM**

The ornamental design for a pediatric examination table, as shown and described.

DESCRIPTION

FIG. 1 is a side elevation of a pediatric examination table embodying the claimed design;

FIG. 2 is a front elevational view thereof;

FIG. 3 is a rear elevational view thereof;

FIG. 4 is a top plan view thereof; and,

FIG. 5 is an isometric view thereof.

The side opposite the side shown in FIG. 1 is identical to FIG. 1 except that it is reversed and lacks any markings. For demonstrative purposes, the isometric view of FIG. 5 shows a storage drawer in a retracted position.
